2 SHEETS—SHEET 2.

UNITED STATES PATENT OFFICE.

DAVID F. CRAWFORD, OF PITTSBURGH, PENNSYLVANIA.

AUTOMATIC SAFETY DEVICE.

1,218,061.

Specification of Letters Patent.

Patented Mar. 6, 1917.

Application filed February 11, 1913. Serial No. 747,825.

To all whom it may concern:

Be it known that I, DAVID F. CRAWFORD, a citizen of the United States, residing at Pittsburgh, in the county of Allegheny and 5 State of Pennsylvania, have invented certain new and useful Improvements in Automatic Safety Devices, of which the following is a specification.

This invention relates to automatic safety devices particularly adapted for use in railway service. It broadly contemplates the provision of an improved means for automatically operating safety mechanism, and signal apparatus and the like, for example 15 at such times as an engineer passes into a closed block.

My invention further contemplates the provision of detector mechanism whereby a record is made of the times the device has 20 been actuated. Among the more specific objects of my invention are the provision of improved means whereby a current of electricity is induced and effects the operation of safety mechanism when the locomotive 25 passes a signal; and the provision of means whereby a signal is automatically actuated in the cab which can not be released without actuating detector mechanism which registers the operation of the signal. 30 The foregoing together with such other objects as may hereinafter appear, or are incidental to my invention, I attain by means of a construction which I have shown in the accompanying drawings in connection with a signal located in the locomotive cab which indicates when the locomotive 35 has passed a signal.

Of the drawings, Figure 1 is a diagrammatic showing of a railroad track, semaphore signal, and locomotive and illustrates the application of my invention thereto and the relation of the various parts with respect to each other; Fig. 2 is a section through the signal device in the locomotive 45 cab, taken on the line II-II of Fig. 3; Fig. 3 is a side elevation of the device shown in Fig. 2 with the cover plate removed; and Fig. 4 is a side elevation of the signal apparatus drawn on a smaller scale 50 and illustrates the method of fastening the covers or lids therefor.

Referring particularly to Fig. 1 the railroad tracks are indicated by the numeral 7, the semaphore post, carrying the semaphore 55 8, by the numeral 9 and the locomotive by the numeral 10. Located between the

tracks 7 is a primary, alternating transformer or induction coil 6 connected to a circuit by means of the wires 11 and 12. The wire 12 leads from the one main wire 60 13 while the wire 11 is connected to the other main wire 14 by means of the contact block 15 mounted on the semaphore 8, the contact block 16 and the wire 17. It will be clear that when the semaphore is in the position indicated in Fig. 1, in which position the red signal is showing, the circuit will be completed by the contact of the blocks 15 and 16.

A secondary coil 18 is supported from 70 the locomotive cab on the bracket 19 in such manner as to pass in close proximity to the primary coil when the locomotive passes the signal. The secondary coil is connected with a magnet 20 by means of 75 the wires 21 and 22. The magnet is mounted in a casing 23 which is located within the cab.

As the locomotive passes the primary coil a current will be induced in the secondary 80 coil from the primary coil and the magnetic device 20 will be actuated. In the present device the magnet operates an annoying signal such as the whistle 24^a by means of the following mechanism: The 85 casing 23 is provided with two ports 24 and 25, communication between which being controlled by means of the plug valve 26. The port 24 is connected to the main reservoir 27 of the locomotive by means of 90 the pipe 28 and the port 25 is connected to the whistle 24^a by means of the pipe 29. The rotary plug valve 26 is provided with an operating arm 30 to the upper end of which is secured a tension spring 31 which 95 is fastened to the casing 23 and normally tends to rotate the valve to open position. In Fig. 3 the valve is shown in closed position at which time air from the reservoir can not pass through the port 25. Slidably 100 mounted in the casing is a release rod 32, the inner end of which is apertured to receive the lower portion of arm 30 of the valve. The rod 32 is provided with a notch 33 which is adapted to receive the end of 105 the bar 34 of the magnet 20, which bar when in the position indicated in Fig. 3 prevents the spring 31 from moving the arm 32 outwardly thereby releasably locking the valve in closed position. When the magnet 20 is 110 energized by the inducing of a current in the secondary coil, the bar 34 of the magnet

is drawn out of engagement with the notch 33 and the spring 31 rotates the valve 26 and communication between the ports 24 and 25 is established and the current of air 5 blows the whistle. The outer end of the release or operating rod 32 lies within the chamber 35 of the casing. When the engineer desires to stop the blowing of the whistle, it will be necessary to unlock the lid 36 of the chamber 35, break the seal 37 and push the rod 32 inwardly until the bar 34 of the magnet 20 drops into engagement with the notch 33, this movement of the rod 32 effecting the closure of the valve 26.

10 As a means for detecting and positively recording the number of times the signal apparatus is actuated, I provide the following mechanism: The port 25 opens out into a cylinder 25^a in which is mounted a piston rod 38 which is provided with a sharpened point 39 and which is normally held in retracted position by means of the spring 40 which bears against the piston head 41. When the valve 26 is opened, the pressure 25 against the piston head 41 advances the piston rod 38 until the point thereof pricks a hole in the paper disk 42 which is detachably carried on the collar 43 mounted on the stud 44 for rotary movement. The stud is 30 screwed into the casing and the collar is provided with a flange 45 which serves to hold in place a disk 46 which is preferably composed of cork or other soft substance. The disk 42 of paper lies on the face of the 35 cork disk 46 so that the piston 38 can readily punch or prick a hole into the paper when the piston is advanced.

The collar 43 is also provided with ratchet teeth 47 which are adapted to be engaged by 40 a weighted pawl 48 pivotally mounted in the swinging arm 49. Pivoted to the free end of the swinging rod is a rod 50 which is slidably supported in a bracket 51 fastened to the casing and which is normally held in retracted position by means of the spring 52. When the valve 26 opens the lower portion 45 of the arm 30 moves in the direction of arrow and the spring 52 forces the rod 50 in the same direction and the pawl 48 ratchets over the teeth 47. When the rod 32 is pushed back to normal position the arm 30 50 engages the end of the rod 50 and moves it forwardly and turns the collar 43 one notch, inasmuch as the pawl 48 will engage one of the ratchet teeth 47 and impart rotary movement to the collar as the rod 50 is being moved. If the engineer should pass another signal the operation just described will be 55 repeated and a second hole will be punched in the disk. It will be noted that with the exception of the end of the rod 32 the entire mechanism is inclosed in the chamber 53 of the casing 23, said chamber being closed by means of the lid 54. The lid 54 is locked 60 and is also provided with a seal 55 and when

the engine is brought to the round house an inspector can open the chamber 53 and check up the report of the engineer, in case the seal 37 has been broken. The purpose of this mechanism for detecting the number of times 70 the signal apparatus has been actuated is to secure greater safety through observance of signals on the part of the engineer, as it will be readily apparent that the engineer will exercise more care with the knowledge 75 that any negligence on his part in this respect will be registered.

In order to prevent the point 39 from scoring the paper disk when the collar 43 is rotated, the valve 26 is so arranged that communication between the ports 24 and 25 is 80 shut off before the arm 30 of the valve abuts the end of the rod 50. The air remaining in the cylinder 25^a will therefore be exhausted and the spring 40 will return the 85 piston 38 to normal position clear of the disk 42 before the rod 50 effects the rotation of the collar 43.

It will be apparent that the means for inducing a current of electricity in the secondary coil is simple and effective and it will be clear that the current thus induced may be readily employed in effecting the operation of a variety of safety devices and signal apparatus of various types. 90

Having thus described my invention and illustrated its use, what I claim as new and desire to secure by Letters Patent is the following:—

1. In railway service, a fluid actuated 100 safety device of the character specified, a fluid actuated recording member, a connection from a source of fluid pressure, a valve for controlling said connection normally held in open position, a trip mechanism for 105 releasably holding the valve in closed position, means for releasing said trip mechanism, and a movable member adapted to be marked by the recording member, said movable member being moved when the trip 110 mechanism is reset.

2. In combination in a safety device for locomotives, a signal, fluid pressure means for continuously operating the signal, a cut-off means therefor, means for holding the 115 cut-off means in position to cut off the supply of fluid pressure, electrically operated means governed by the position of the locomotive for releasing the said means to supply fluid to the signal, a movable recording 120 device for indicating the operation of the signal, and means whereby the resetting of the cut-off holding means advances the recording device in position for further recording.

3. In railway service, the combination with a signal device and a recording device, of means for simultaneously actuating the signal and the recording device to register the actuation of the signal upon a record, 130

means for starting the actuation of the signal and recording devices, separate means for stopping the signal actuation, and separate means operated by such means for moving the record into another operative position.

4. In combination in a signal apparatus for railway service, a signal, a record, a means for perforating the record, means for simultaneously actuating the signal and the record perforating means, manually operable means for stopping the signal device adapted to move the record, and means for retracting the perforating means before the record moving means is actuated.

5. In a safety device, a signal, a recording mechanism for registering the operations of

the signal, comprising a movable record, a recording member adapted to mark the record, fluid means for actuating the signal and recording member, a valve controlling the fluid, means for automatically opening such valve to operate the signal and the recording member, manually operable means for closing the valve and means actuated by the valve closing means for moving the record.

In testimony whereof I have hereunto signed my name in the presence of the two subscribed witnesses.

DAVID F. CRAWFORD.
